UNITED STATES PATENT OFFICE.

DAVID A. GREEN AND JAMES H. ROBERTS, OF RUSHVILLE, INDIANA.

HINGE.

SPECIFICATION forming part of Letters Patent No. 225,980, dated March 30, 1880.

Application filed April 9, 1879.

To all whom it may concern:

Be it known that we, DAVID A. GREEN and JAMES H. ROBERTS, of Rushville, in the county of Rush and State of Indiana, have 5 made and invented certain new and useful Improvements in Hinges; and we do hereby declare that the following is a full, clear, and exact description of the invention, which will enable others skilled in the art to which it 10 appertains to make and use the same, reference being had to the drawings here accompanying, and to letters of reference marked thereon, which form a part of this specification.

This hinge is susceptible of being used on 15 a variety of folding articles, especially adapted to step-ladders, folding cots, cabinet and folding beds, &c.

The following is a description of our newly-invented double-acting lock or drop hinge.

20 Figures 1 and 2 represent the two sections of the hinge detached, showing one manner of connecting them together, the head B' of section A' being provided with a hole of suitable size to receive the metal pin in the head of B² of section A², said pin being riveted, making them securely fastened together, and also forming a pivot for the hinge. The head B² of section A² may be provided with a hole, the same as

hinge, while standing as shown in Fig. 3, admitting of the two sections H H being folded together, as shown in Fig. 4, and when dropped or turned down, as indicated by the dotted lines in Fig. 3, making a complete lock or 40 stiffening of the joint.

Fig. 4 represents the hinge attached to two sections, H H, of a cabinet or folding bed rail folded together, the hinge being provided with holes for the purpose of fastening boards E 45 E, as shown by dotted lines in Fig. 3, of sufficient width to fill the space between the rails H H when folded up. When opened or extended the boards E E turn down with the hinge, as shown by dotted lines E E, Fig. 3, 50 thus forming a narrow rail and a positive lock.

Having thus described our invention, what we claim as new and useful, and desire to secure by Letters Patent, is—

A hinge consisting of sections A' A², each 55 composed of converging arms, which are provided at their outer ends with half butts or hinges D D, and whose heads B' B² are joined together by bolts or rivets, the whole forming a double-acting hinge, as described, and for 60 the purposes set forth.

In testimony that we claim the foregoing as our own we have hereto affixed our signatures

B' of section A', and the two sections fastened 30 together by means of a bolt or rivet.

Fig. 3 represents the hinge attached to two sections, H H, of a cabinet-bed rail by means of four half butts or hinges, D D D D, by means of screws passing down through the butts D 35 D D and into the top of said rails H H, the

in presence of two witnesses.

DAVID A. GREEN.
